UNITED STATES PATENT OFFICE

CARL G. HILGENBERG, OF BALTIMORE, MARYLAND, ASSIGNOR TO CARR-LOWREY
GLASS CO., OF BALTIMORE, MARYLAND

GLASS CONTAINER

Application filed January 2, 1931. Serial No. 508,249.

This invention relates to glass containers of that type employing screw caps.

As glass containers are formed in molds they are produced with protruding seams or minute beads where the mold members come together. Thus when a container has been formed with a threaded neck finish, these protruding seams have appeared on the threads and cut into and mutilated screw caps formed of "Balselite" and like materials such as now generally used. This has interfered with the proper sealing action of the cap engaging the thread. As a means for avoiding this objectionable feature it has been the practice to mold glass containers with "jump" threads. In other words the threads are eliminated at the seams so that there will be no portion of the glass protruding beyond the threads. This structure has not been entirely satisfactory, however, because it has weakened the neck portion and left portions of the threaded cap fully spaced from the neck finish.

It is an object of the present invention to combine the advantages of a continuous thread and a "jump" thread without having the disadvantages resulting from the formation of a protruding seam.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing the preferred form of the invention has been shown.

In said drawing:

Figure 1 is a plan view of a container having the present improvements, the protruding seam being exaggerated for the purposes of illustration.

Figure 2 is an elevation of the container, the protruding seam being exaggerated.

Referring to the figures by characters of reference, 1 designates a container which can be of any desired configuration. The neck

2 of the container has a continuous thread 3 molded thereon but at those points where the protruding seam 4 extends across the thread, said thread is reduced in size as shown at 5 so that the protruding portion 55 of the seam will not extend beyond continuations of the faces of those portions of the thread which are not reduced. Thus it will be seen that when a screw cap is placed in engagement with the threaded neck the seam 60 will not engage and bite into the cap. However the thread will have the advantages of both a continuous thread and a "jump" thread.

In practice it has been found possible to 65 extend the reduced portion not more than 10° each side of the seam or joint. It has also been found that the main thread can be made longer and thus provide more bearing surface for the screw cap than where a 70 "jump" thread is used, thereby insuring a better connection.

What is claimed is:

1. A glass container having a neck provided with a seam and a screw thread molded 75 on the neck and extending therearound, that portion of the thread crossed by the seam being reduced in size to an extent not less than the height of the seam.

2. A glass container having a continuous 80 screw-threaded neck finish and a seam extending across the thread, those portions of the thread crossed by the seam being reduced to support all of the protruding portions of the seam within the area defined by the 85 threads.

3. A glass container having a continuous thread on the neck portion thereof, there being a protruding seam on the neck portion 90 and extending across the thread, said thread being so shaped as to prevent protrusion of the seam beyond the outermost surfaces of the thread.

In testimony that I claim the foregoing as 95 my own, I have hereto affixed my signature.

CARL G. HILGENBERG.
